Edward Ode
Inventor

UNITED STATES PATENT OFFICE.

EDWARD ODE, OF ORLAND, CALIFORNIA.

FINGER-MOISTENING MACHINE.

1,323,645.

Specification of Letters Patent.

Patented Dec. 2, 1919.

Application filed May 20, 1919. Serial No. 298,540.

To all whom it may concern:

Be it known that I, EDWARD ODE, a citizen of the United States of America, residing at Orland, in the county of Glenn and 5 State of California, have invented a new and useful Finger-Moistening Machine, of which the following is a specification.

My invention relates to improvements in finger moistening machines for moistening 10 finger tips for the purpose of turning pages or documents, or papers or currency, or any other thin materials, the turning of which is facilitated by moistening of the finger tips, by means of a felt pad kept moist by 15 water from a small reservoir; and the objects of my improvement are, first, to provide a moistener which can be worn on the hand in such manner as to leave the fingers entirely free and unencumbered for writing, 20 operation of adding machine, or other office work; second, to facilitate moistening of finger by a motion of finger only, thereby avoiding necessity of reaching for moistener, or moistener being out of reach and thus 25 giving occasion for unsanitary habit of moistening finger on lips; third, to provide a moistener to be worn in palm of hand and be held in position in such a way as to be almost invisible from back of hand.

30 I attain these objects by the mechanism illustrated in the accompanying drawing, in which—

Figures 1 to 5 are details of the device.

Fig. 6 a plan, and Fig. 7 a section of the 35 same, while Fig. 8 shows the reservoir.

Similar numerals refer to similar parts throughout the several views.

The water reservoir 8, has bottom 10, curved to fit palm of hand, and bands 9, 40 curved to fit sides of hand to hold reservoir in palm of hand. By slightly bending the bands 9, they are adjusted to fit any hand. Top of reservoir 8, is flat and has a water hole 5. Around water hole 5, is mounted a 45 socket 4, threaded on inside to match pad holder 6.

Pad holder 6 (detailed at Fig. 5), is threaded on outside to screw into socket 4, and over water hole 5, bringing the felt pad 50 7, into contact with water from reservoir. Pad holder 6 has a narrow rim 2, on top to hold pad 7, in place. On top of rim 2, are two thumb knobs 1, to facilitate screwing

and unscrewing pad holder when filling reservoir with water. On bottom side of pad 55 holder 6, is a cross of narrow strips 3, which keep pad 7, in holder from bottom, and prevent pad from pressing into water hole 5, and choking off supply of water.

Felt pad 7, is inserted into pad holder 6, 60 between 2 and 3 and absorbs water from reservoir 8, through water hole 5. When moistener is in position on hand, felt pad 7, comes directly under and moistens tip of second finger.

Construction to be of aluminum or other light material.

I am aware that prior to my invention finger moisteners to be set on desks have been made, and also devices to be attached 70 to fingers for purpose of turning leaves, etc.

I claim:

1. The combination in a finger moistener of a water reservoir adapted to be worn in the palm of the hand and provided with 75 holder bands extending around sides to back of hand, and provided with a water hole, around which is mounted a socket to receive a pad holder, into which is inserted an absorbent pad to be held in position by means 80 of a narrow rim on top side and on bottom side a cross of metal strips, substantially as described.

2. In a finger moistener, a water reservoir adapted to be worn in the palm of the hand 85 and having in its front side a water outlet and an absorbent element covering the same, and means for securing said reservoir to the hand.

3. The combination in a finger moistener of a water reservoir adapted to be worn in the palm of the hand, with holders extending around each side of hand, and a pad holder mounted directly over a water hole in reservoir and having a narrow rim on top side to hold pad in position, and a cross of 95 metal strips on bottom side to prevent pad pressing into water hole and choking off water supply, substantially as described.

4. The structure specified in claim 2, said 100 securing means consisting of two flat curved clasping metal arms secured to the reservoir and arranged to clasp one over each side of the hand and reach partly upon the back of the same.

EDWARD ODE.
